ATTORNEY

UNITED STATES PATENT OFFICE.

GEORGE HOLLAND, OF LACONIA, NEW HAMPSHIRE.

PUZZLE.

1,260,541.

Specification of Letters Patent.

Patented Mar. 26, 1918.

Application filed May 29, 1917. Serial No. 171,768.

To all whom it may concern:

Be it known that I, GEORGE HOLLAND, a citizen of the United States, residing at Laconia, in the county of Belknap and State 5 of New Hampshire, have invented certain new and useful Improvements in Puzzles, of which the following is a specification.

This invention relates to puzzles and particularly to numerical puzzles.

10 The primary object of the invention is to provide a puzzle which shall prove difficult to solve without knowing the proper combinations, and yet which will prove interesting and instructive to those attempting to discover the proper solution.

15 The invention consists generally in the arrangement of a plurality of members in separate rows, so that the sum total of the numbers in each row when added in one 20 direction will be equal, while the sum of the difference between the numbers of the said rows will be equal to the sum of each row.

25 With these objects in view together with others which will appear as the description proceeds, the invention resides in the novel formation, combination and arrangement of parts all as will be described more fully hereinafter illustrated in the drawings, and particularly pointed out in the claim.

30 In the drawing:

Figure 1 is a plan view illustrating the blocks which are used in carrying out the invention,

35 Fig. 2 is a sectional view taken substantially on line 2-2 of Fig. 1,

Fig. 3 is a plan view illustrating certain of the blocks removed from the container, and arranged so as to show the solution of the puzzle, and

40 Fig. 4 is a plan view of certain of the blocks which are not essential in solving the puzzle.

Referring now to the drawing, 5 indicates a suitable container, the same being in the 45 form of a box of shallow depth as shown, and which box is closed by a lid or cover 6.

Arranged within this box or container are a plurality of blocks indicated generally at 7, and which blocks bear certain indicia. 50 Certain of the blocks bear the "plus" mark and others are provided with the mark of equality, while the remaining blocks are provided with numbers. Three of the blocks bear the number "45," while the remaining 5 blocks bear numbers of lesser value. The

blocks are numbered so that two rows of ten blocks each may be provided, the numbers in each row being 1, 2, 3, 4, 5, 6, 7, 8, 9 and 0. While certain other of the blocks are numbered so as to provide a row of ten 60 blocks numbering 0, 2, 4, 6, 9, 1, 3, 5, 6 and 9. The remaining blocks in the container may be provided with any suitable numbers, these blocks being illustrated in Fig. 4 of the drawing, and are merely included 65 in the set to make the puzzle more confusing.

The end to be attained with the puzzle apparatus is, "how can the number 45 be subtracted from itself and still leave 45?" 70 To accomplish such a result, which seems impossible, the blocks bearing their numbers are arranged in the order shown in Fig. 3 of the drawing. The first row of blocks is arranged with the numbers "1" to "0" 75 consecutively with the "plus" blocks arranged between the numbered blocks. At the end of the row an "equality" block is placed, and beyond the "equality" block is positioned one of the blocks bearing the 80 number "45." In other words, the sum total of the numbers in this row equals "45." Directly below this row of blocks is positioned another row, the numbers of the second row being in inverse order. At the end of this 85 second row is placed one of the sum total "45" blocks. It will be observed, also, that the "plus" blocks are inserted between the numbers of the second row and the "digits" of the second row are disposed directly beneath the digits of the first row. A third row of blocks is disposed beneath the second row, and these blocks are arranged in order as follows: 0, 2, 4, 6, 9, 1, 3, 5, 6, 9, at the end 90 of which row is placed an "equality" mark 95 and a block bearing the number "45". This third row also includes the various "plus" blocks between the various numbers in the said row. If desired, a strip 8 may be inserted between the second and third rows, 100 so as to readily distinguish the same.

By adding the numbers in all three of the rows respectively, it will be observed that the sums will be "45," but when arranged in the manner shown in Fig. 3, if 105 the numbers in the second row be subtracted from the numbers of the first row, the remainder will be equal to the numbers indicated upon the blocks directly beneath the blocks of the second row. The sum of the 110

numbers upon the blocks of the third row is equal to "45," or the sums of the added numbers in the first and second rows.

It is obvious that a puzzle of this character will prove very confusing, but will be entertaining and instructive. The sum total of "45" has been used in the present instance, but it is to be understood that a greater or less number of blocks, not shown in the drawing, may be used if desired, and it will also be understood that numbers of greater or less value may be employed.

What is claimed is:

A puzzle device comprising two sets of blocks, the blocks of each set being num-

bered 1, 2, 3, 4, 5, 6, 7, 8, 9, 0 respectively, a third set of blocks numbered 1, 2, 3, 4, 5, 6, 7, 9, 0, a block bearing the number 45 for each of said sets, blocks having the plus symbol thereon for each of said sets and being adapted to be placed between the consecutively numbered blocks therein, and a block for each set having the mark of equality thereon, substantially as described.

In testimony whereof I affix my signature in presence of two witnesses.

GEORGE HOLLAND.
